DESIGN FOR A HAT

Aaron Rothchild, New York, N. Y., and George J.
Goldberg, Fall River, Mass.

Application November 6, 1941, Serial No. 104,052

Term of patent 7 years

To all whom it may concern:

Be it known that we, Aaron Rothchild and George J. Goldberg, both citizens of the United States, residing, respectively, at New York city, in the county of the Bronx and State of New York, and Fall River, in the county of Bristol and State of Massachusetts, have invented a new, original, and ornamental Design for a Hat, of which the following is a specification, reference being had to the accompanying drawing, forming part thereof.

Fig. 1 is a top plan view of a hat, showing our new design.

Fig. 2 is a front view thereof.

We claim:

The ornamental design for a hat, substantially as shown.

AARON ROTHCHILD.
GEORGE J. GOLDBERG.
